UNITED STATES PATENT OFFICE.

JAMES PIERPOINT, OF PITTSBURG, PENNSYLVANIA.

STEAM-BOILER.

SPECIFICATION forming part of Letters Patent No. 548,455, dated October 22, 1895.

Application filed October 31, 1894. Serial No. 527,526. (No model.)

To all whom it may concern:

Be it known that I, JAMES PIERPOINT, of Pittsburgh, in the county of Allegheny and State of Pennsylvania, have invented a new and useful Improvement in Steam-Boilers, of which the following is a full, clear, and exact description, reference being had to the accompanying drawing, forming part of this specification, in which the figure is a vertical 10 longitudinal section of my improved boiler.

My invention relates to vertical water-tube boilers, and is designed to simplify, cheapen, and improve their construction.

To that end it consists in an upper steam 15 and water drum, a lower mud-drum, a bank of tubes connecting these drums, and a partition-wall located between the tubes of the bank and arranged to cause an up-and-down pass of the furnace-gases over the tubes and 20 by keeping certain of the tubes in a cooler place insure a strong circulation and efficient abstraction of heat.

In the drawing, 2 represents the upper steam and water drum, 3 the mud-drum, and 25 4 the bank of tubes connecting the same. Between the central rows of this bank is placed the transverse fire-brick partition 5, which extends from the mud-drum upwardly to a point near the steam and water drum.

30 6 is the furnace, from whence the gases pass upwardly among the front rows of the bank, then descend among the rear rows, and thence ascend through the outlet-flue 7. Deflecting-plates 8 are employed to hold the gases in 35 contact with the tubes, thus insuring the abstraction of heat thereby.

In the steam and water drum I provide a vertical longitudinal baffle-plate 9, which is preferably bolted to the inside of the shell by 40 angle-irons 10 at the ends and extends upwardly to a point above the water-level. This plate extends between the tube ends, and the feed-water entering through the pipe 45 11 on the left-hand side of the plate is prevented thereby from mingling with the hotter

water rising through the tubes nearer the furnace, but descends through the rear rows in a less violent manner than in the main circuit, from which it is cut off by the baffle-plate, thereby giving a much better deposition of 50 sediment.

The heat of the gases is fully extracted on account of the lower temperature of the rear tubes down which the feed-water passes, while a violent circulation takes place between the front rows and these rear rows, 55 which are not cut off by the baffle-plate.

The advantages of the invention are apparent, the arrangement of the parts being simple, compact, and highly effective. 60

I claim—

1. A water-tube boiler comprising an upper transverse steam and water drum, a lower mud drum, a series of substantially parallel tubes connecting these drums, a vertical transverse partition between the tubes, and deflecting plates arranged to hold the gases among the tubes; substantially as described. 65

2. A water-tube boiler comprising an upper transverse steam and water drum provided 70 with a vertical baffle-plate extending to the bottom of the drum, a lower mud drum, tubes connecting these drums, and a vertical transverse partition between the tubes; substantially as described. 75

3. A water-tube boiler comprising an upper transverse steam and water drum provided with a vertical baffle-plate extending above the water level and a feed-pipe entering on one side of the plate, a lower mud drum, tubes 80 connecting these drums, and a vertical transverse partition between the tubes; substantially as described.

In testimony whereof I have hereunto set my hand.

JAMES PIERPOINT.
